VACUUM-CONTROLLER FOR PNEUMATIC CLEANING APPARATUS.

1,014,729.

Specification of Letters Patent.

Patented Jan. 16, 1912.

Application filed March 2, 1908. Serial No. 418,819.

To all whom it may concern:

Be it known that we, JOHN S. THURMAN and JOHN A. DUNLAP, citizens of the United States, and residents of St. Louis, Missouri, **5** have invented certain new and useful Improvements in Vacuum-Controllers for Pneumatic Cleaning Apparatus, of which the following is a specification containing a full, clear, and exact description, reference **10** being had to the accompanying drawings, forming a part hereof.

Our invention relates to a vacuum controller for pneumatic cleaning apparatus.

The object of our invention is to provide **15** simple valves for automatically regulating the flow of air or steam to the apparatus, thereby correspondingly regulating the vacuum in the vacuum tank, and which automatic regulation prevents a waste of the **20** energy necessary to create the vacuum, as the action of the automatic valves is dependent upon the amount of air admitted to the apparatus.

To the above purposes, our invention **25** consists in certain novel features of construction and arrangement of parts, which will be hereinafter more fully set forth, pointed out in the claims, and illustrated in the accompanying drawings, in which:—

30 Figure 1 is a front elevation of a cleaning apparatus equipped with our invention; Fig. 2 is a vertical section taken through the center of the automatic control valve; Fig. 3 is a vertical section taken on the line 7—7 **35** of Fig. 6; Fig. 4 is a horizontal section taken on the line 8—8 of Fig. 6; Fig. 5 is a plan view of the vacuum control valves, with the top plate removed.

Referring by numerals to the accompanying **40** drawings:—1 designates a suitable frame mounted on wheels 2, in order that it may be readily moved from one position to another as desired; and arranged in said frame is a box or container 4, which is intended to **45** receive the sweeper or cleaning tools and hose utilized in connection with the cleaning apparatus.

Fixed on the frame 1 in front of the box **50** 4 is a platform 5; and supported thereon is a vertically disposed vacuum tank 6, which is cylindrical in form, and provided at its lower end with a discharge spout 7, at the lower end of which is arranged a detachable door 8, which is perfectly air tight

when closed. The upper end of the tank **55** 6 is closed by means of a plate 9, with the central portion of which is formed integral a vertically disposed ring 10; and the upper end of said ring 10 is closed by an integral plate 11, in which there is formed a valve **60** seat for a gravity ball valve not shown.

Formed integral with the rear portion of the ring 10 is a housing 16, and communicating with the chamber therein and leading downward from the plate 9 is an open ended **65** tube not shown, leading to a dust filter 18, composed of a sack of coarse fabric, which is connected at its upper end to the lower end of the ring 10.

Connected by a nipple to the top of the **70** housing 16 is a Y-connection 21, on the ends of which are carried valves 22, which are adapted to receive the ends of flexible tubes, which lead to the sweepers or cleaning tools.

Connected to the upper end of the valve **75** 14 housing 14 is one end of a horizontally disposed tube 25, the opposite end of which curves downward and is connected to the upper end of a short tube 26; and connected to the lower end of this tube 26 is **80** the upper end of a tube 27, the opening into the upper end of which is funnel-shaped, as designated by 28. The lower end of the tube 27 is connected to a muffler 29.

Formed integral with the top of the tube **85** 26 is a horizontally disposed plate 32, and formed integral with and depending from this plate is an air valve housing 33, the lower end of which is normally closed by a screw plug 34, in which is formed an air **90** inlet aperture 35. Tapped into the side of this housing 33 is a compressed air or steam pipe 36, and leading from the opposite side of said housing 33 and formed integral therewith, and with the tube 26, is a tube **95** 37, which is extended to the interior of said tube 26, as designated by 38; and screw seated in the lower end of the extension 38 is a nozzle 39, which is positioned in the center of the funnel-shaped opening 28 in **100** the upper end of the tube 27.

Fixed on top of the plate 32 is a cylindrical housing 40, and arranged for operation in the lower portion of the chamber therein is a valve 41, to the center of which is connected the upper end of a stem 42 which operates through an aperture formed in the plate 32, immediately above the center of the

valve housing 33; and carried by the lower end of said stem 42 and operating in the housing 33, is a cylindrical valve 43, provided in one side with a port 44, adapted to coincide with the opening through the tube 37; and formed in the opposite side of this valve 43 is an elongated port 45, which communicates with the opening in the air or steam pipe 36.

10 Formed through the plate 32 are apertures 46, which permit atmospheric pressure to pass to the interior of the housing 40 beneath the valve 41. Operating through the top of the housing 40 is a set screw 47, and carried by the lower end thereof is a disk 48, and there being an expansive coil spring 49 arranged between said disk and the valve 41.

15 Fixed to the front side of the housing 40 is a casing 50, in the center of which is formed a pair of vacuum chambers 51 and 52, the latter being immediately to the rear of the chamber 51, and communicating with the chamber in the housing 40 by means of a port 53. Leading from the chamber 51 to the chamber within the ring 10 is a tube 54.

20 Formed integral with the ends of the casing 51 are vertically disposed cylindrical valve housings 55 and 56, the lower portions of which are interiorly screw threaded; and adjustably located within the screw threaded portions of said housings are tubular nuts 57, and the lower ends of said cylinders are 25 closed by screw plugs 58.

25 Formed integral with the top of the casing 50 and with the upper ends of the housings 55 and 56 is a horizontally disposed plate 59, in the top side of which are formed shallow compartments 60 and 61, corresponding to the housings 55 and 56; and arranged over said shallow compartments is a 30 pair of diaphragms 62, held in place by a plate 63 in which are formed apertures 64 35 immediately above the center of each diaphragm.

40 Formed through the plate 59, above the chamber within the housing 55, is an opening 65, the upper edge of which is beveled to 45 form a seat for a disk valve 66, which normally bears against the under side of the diaphragm in the compartment 60, and the stem of said valve passes downward through a nut 67; and said stem terminating in the 50 tubular nut 57. Arranged between the tubular nut 57 and the nut 67 is an expansive coil 55 spring 68.

55 Formed through the plate 59, above the chamber within the housing 56, is an opening 69, the lower edge of which is formed into a seat for a valve 70, through which 60 passes a stem 71 carried by a disk 72, which latter occupies the compartment 61 beneath the diaphragm therein. Interposed between the valve 70 and the tubular nut 57 in 65

the lower portion of the housing 56 is an expansive coil spring 73, which is of greater tension than is the spring 68, (previously described.)

70 Formed through the plate 59 is a port 74, which establishes communication between the chambers 51 and 60, and a second port 75 formed through said plate 59 establishes communication between the chambers 51 and 61. A port 76 is formed through one of the 75 side walls of the casing 50 and establishes communication between the chamber 52 and the interior of the housing 55; and a similar port 77 is formed through the opposite side wall of the casing 50, and establishes communication from the chamber 52 to the interior of the housing 56.

75 To secure the best results in the use of a cleaning apparatus constructed as herein described, it is necessary to maintain approximately twelve inches of vacuum in the tank 6, and this is accomplished by closing the valves 22 and turning on the air or steam through the pipe 36; and said air or steam passes through the ports 45 and 44 in the 80 cylindrical valve 43, from thence through the tube 37 and extension 38, to and through the discharge nozzle 39, from thence through the tube 27, and from thence into the muffler 29; and, after passing therethrough, it 85 discharges through the openings in the outer shell. The jet of compressed air or steam issuing from the nozzle 39 into the funnel-shaped upper end 28 of the tube 27 creates a suction and consequent vacuum within 90 the tank 6 by exhausting the air which is drawn through the ring 10, housing 14, (the gravity valve being opened by the suction,) tube 27, tube 26, and tube 25; and the air thus withdrawn from the interior of the 95 tank 6 is carried along with the air or steam discharging from the nozzle 39. As soon as the proper vacuum has been established within the tank 6, the tools carried on the 100 ends of the flexible tubes are put into service; and when the inlet valves of said tools are opened, the vacuum in the tank 6 creates suction through the Y-connection 21, through the valve or valves 22 which have 105 been opened, through the corresponding flexible tubes, and through the tools which are in use; and, as a result, the dust and like foreign matter is by suction drawn through the inlet openings or slots in the tools, and passes through the flexible tubes, Y-connection 21, and to the interior of the vacuum tank 6; and said dust and like foreign matter is caught by a dust filter of common construction; and the air drawn into the tank 6 during the cleaning action is delivered, (as 110 hereinbefore described,) to the muffler, from whence it is discharged.

115 The action of the automatic control valves for regulating the position of the valve 43 is as follows:—The vacuum maintained in 120

the tank 6 is maintained in the compartment 51 by reason of the tubular connection 54, which leads to said compartment from the ring 10, and said vacuum is also maintained in the compartments 60, and 61 through the ports 74 and 75. The valve 66 is normally held open by the spring 68, and, therefore, vacuum is established within the housing 55; and by reason of the port 76, 10 said vacuum is maintained in the chamber 52; and by reason of the port 53, vacuum is maintained within the housing 40. The vacuum within the housing 40 permits the atmospheric pressure entering ports 46 to 15 elevate the plunger valve 41; and, as a result, the valve 43 is drawn upward through the housing 33, thus materially reducing the flow of compressed air or steam through said control valve; and as soon as this action takes place, the degree of vacuum is 20 proportionately decreased, and an equilibrium established. The tension of the spring 68 is so adjusted by means of the tubular nut 57 that it will be overcome by the closing 25 of the valve 66 at a predetermined amount of vacuum; and when said valve is closed, vacuum is no longer maintained in the chamber 52 and in the chamber within the housing 40; and, as a result, the spring 30 49 expands and moves the plunger valve 41 downward, thus increasing the flow of compressed air or steam through said valve, which, (as hereinbefore described,) produces greater vacuum within the tank 6 and 35 the various parts of the control valves. The vacuum maintained within the chamber 51 is maintained in the compartment 61; and, as a result, this vacuum draws the corresponding diaphragm 62 downward and 40 forces the valve 70 open. When a predetermined amount of vacuum thus overcomes the resistance offered by the spring 78, which is set at higher tension than is spring 68, and when said valve 70 is thus forced 45 open, a corresponding degree of vacuum is established in the chamber 52, by reason of communication through the port 77; and by reason of the port 53, the same degree of vacuum is established in the chamber with- 50 in the housing 40, thus permitting the atmospheric pressure to act and operate the plunger valve 41, together with the valve 43, which cuts off the passage of air or steam through said air valve, and conse- 55 quently reducing the amount of vacuum created. These automatic valves accurately control the flow of air or steam through the valve 43, thereby accurately and correspondingly regulating the degree of vacuum ac- 60 cording to the number of sweepers or tools in use; and when there are no sweepers or tools in use, the supply of air or steam is entirely cut off, thus preventing the waste of energy necessary to establish a partial vacu- 65 um. When one or more sweepers or tools

are in operation, the action of the valve 66 controls the action of the valve 43; and as the vacuum increases or diminishes, said valve raises or lowers correspondingly to open or close the ports through said valve. 70 When there are no sweepers or tools in operation, the valve 66 will close at a predetermined vacuum, and valve 70 will open at a predetermined vacuum, which is of a higher degree than the vacuum required to 75 close the valve 66, which action maintains the same degree of vacuum within the chamber in the housing 40, thus instantly closing the valve 43.

Our improved cleaning apparatus is especially applicable for use in cleaning cars, residences, and the like, as it can be readily transported from one point to another; and, when in use, the degree of vacuum necessary to the successful operation of the apparatus is accurately maintained by the automatic valves which control the flow of compressed air or steam necessary to create the vacuum.

By mounting an apparatus of our improved construction on a suitable truck and arranging an exhaust pump on the truck and connecting the vacuum tank with said pump, the apparatus can be utilized for cleaning paved streets and the like. When the apparatus is so used, special forms of nozzles are arranged on the ends of the flexible tubes.

We claim:—

1. In an apparatus of the class described, the combination with a vacuum pipe and a vacuum-creating fluid-conductor, of a valve for controlling the flow of liquid through said conductor, a housing in communication with the vacuum pipe, means located in said housing and influenced by the vacuum for the operation of said valve, and a pair of spring controlled valves influenced by the vacuum for controlling the degree of vacuum in said housing, the springs for controlling said valves being of different tensions whereby the spring of the least tension will control a predetermined normal vacuum and the spring of greater tension control a predetermined maximum vacuum. 100
2. In an apparatus of the class described, the combination with a vacuum pipe and a vacuum-producing fluid-conductor arranged to discharge into the vacuum pipe, of a cut-off valve for controlling the passage of fluid 105 through said last mentioned conductor, spring controlled means influenced by the vacuum for operating said valve, a housing for containing said means and a pair of spring controlled valves influenced by the 110 vacuum for controlling the degree of vacuum in said housing, the springs of said last mentioned valves being of different tensions, whereby one valve is arranged to control the cut-off valve at a predetermined nor- 115
3. In an apparatus of the class described, the combination with a vacuum pipe and a vacuum-producing fluid-conductor arranged to discharge into the vacuum pipe, of a cut-off valve for controlling the passage of fluid 120 through said last mentioned conductor, spring controlled means influenced by the vacuum for operating said valve, a housing for containing said means and a pair of spring controlled valves influenced by the 125 vacuum for controlling the degree of vacuum in said housing, the springs of said last mentioned valves being of different tensions, whereby one valve is arranged to control the cut-off valve at a predetermined nor- 130

4
mal vacuum and the other valve arranged to control the cut-off valve at a predetermined maximum vacuum, and means for varying the tensions of said springs, whereby said valves will be operated at different normal and maximum degrees of vacuums.

In testimony whereof, we have signed our

names to this specification, in presence of two subscribing witnesses.
